UNITED STATES PATENT OFFICE.

STEPHEN D. HARTOG, OF BELLEVILLE, ILLINOIS, ASSIGNOR TO JOHN W. MARSH, OF BELLEVILLE, ILLINOIS.

STENCIL-CUTTING MACHINE.

Application filed January 23, 1922. Serial No. 531,025.

To all whom it may concern:

Be it known that I, STEPHEN D. HARTOG, a citizen of the United States, residing at Belleville, St. Clair County, and State of Illinois, have invented a new and useful Stencil-Cutting Machine, of which the following is a specification.

This invention relates to improvements in stencil cutting machines, and consists in 10 the novel construction hereinafter disclosed.

An object of the invention is to provide a stencil cutting machine designed so that the work will be visible to the operator.

Another object of the invention is to provide 15 a machine of the class described having the operating mechanism for the paper feed and stencil cutting operations arranged below the base frame of the machine.

Another object of the invention is to provide 20 in a machine of the class described operating mechanism that may be operated either by a right hand or a left hand operator, said operating mechanism being so disposed so that the facility and rapidity 25 of the operation of the machine will be increased.

Another object of the invention is to improve 30 in a machine of the class described the work feeding mechanism.

Other objects of the invention will be 35 apparent from the following detailed description of the invention taken in connection with the accompanying drawings, in which

Fig. 1 is a plan view of the machine.

Fig. 2 is a bottom plan view of the machine.

Fig. 3 is a vertical section through the machine.

Fig. 4 is an enlarged vertical section of 40 the work feeding mechanism and the stencil cutting mechanism.

Fig. 5 is a detailed view of one of the die supports and guides.

Fig. 6 is a plan view of the same element.

Fig. 7 is a transverse section through the work feeding mechanism.

Fig. 8 is a detailed view of a portion of the work feeding mechanism.

Fig. 9 is a detailed view of the stripper device.

In the embodiment of the invention illustrated in the drawings the base frame of the machine is shown as comprising a cast-

ing 1 having an extension 2 for supporting the operating mechanism. The base of the machine is substantially semi-circular in form and is suitably reinforced by ribs 3, as clearly shown in the drawings, so as to provide a rigid frame for supporting the stencil cutting mechanism. An extension 2 of the frame is integrally formed therewith providing a suitable support for the work feeding and the operating mechanism for the stencil cutting mechanism. The base 6 of the frame includes a central support 4 for one end of a spindle 5 which is rigidly mounted therein. The spindle 5 carries a hub casting 6 to which is secured an annular die carrier 7, said die carrier 7 being made up of a central annular flange 8, a webbed section 9 and an outer annular ring 10. The flange 8 matches the hub 6 and is screwed thereto by a series of screws 11, thereby forming a rigid connection between the die carrier and the hub 6. Above the die carrier is a circular plate 12 constituting the punch carrier. A hand wheel 13 with a depending flange 14 is arranged to be secured to the punch carrier, there being provided on the flange 14 of the hand wheel a horizontally disposed flange 15 that fits over an annular boss 16 carried by the plate 12. A series of screws 17 passing through the flange 15 and into the annular boss 16 serve to secure the two parts together.

The upper end of the spindle 5 is formed with a reduced portion 18 over which is fitted a character dial-carrying member 19. The member 19 is in rigid connection with the spindle 5, being secured thereto by a screw 20 bearing against a washer 21, the screw 20 being threaded into a threaded opening in the end of the spindle. Adjacent to the outer periphery of the dial member 19 is a series of character indices 22, and arranged on the inner wall of the flange 14 of the hand wheel is a pointer element 23 adapted, in cooperation with the dial, to indicate the position of the respective stencil cutting character punch and dies.

In order to facilitate the rotation of the punch and die carrying elements a ball bearing structure 24 is mounted intermediate the lower face of the hub 6 and the upper face of the support 4.

It will be understood that the hub 6 is rotatably mounted upon the central portion of

the spindle 5 and that by means of the hand wheel 13 the hub 6, together with the punch and die carriers, will be rotated to bring the selected punch and die members in position in respect of the work for the stencil cutting operations.

The stencil cutting punch elements 25 are mounted in an annular equally spaced series on the under face of the punch carrier 12 adjacent to the periphery thereof, the said punch elements being separately secured to the carrier by bolts 26 passing through the wall of the carrier 12.

The outer ring 10 of the die carrier has a channel 27 formed therein so as to constitute a bifurcated die support including the lower wall 28 and the upper wall 29.

It will be noted that the upper face of the wall 29 is inclined, the purpose of which is to deflect the cuttings from the work so that the waste material will pass downwardly through the frame of the machine and onto the support by which the machine is carried. It is with a view to disposing of the waste material, by permitting it to drop through the frame of the machine, that the portion 9 of the carrier 7 is made in a webbed formation so that the material will pass through the openings between the webs. This disposal of the waste material prevents accumulation of such material so as to avoid interference with the operating parts of the machine.

The die element is shown in detail in Figs. 5 and 6 and includes a die support in the form of a U-shaped member 30 having a side flange 31 and an extended flange 32 deflected downwardly forming a tang 33. The die plate 34 is screwed to the upper face of the flange 31 and the extension 32, the opening in the die plate being over the channel of the U-shaped member 30 so that the waste material cut from the work will pass downwardly into the space between the side walls of the member 30, striking the inclined face of the wall 29. The die member further includes a shank 35, said shank having a groove 36 formed therein, and a reduced portion 37 terminating in a pointed extremity 38. The die members are mounted in the die carrier with the shank 35 passing through spaced openings in the walls 28 and 29. For each die member there is provided a strong expansion spring 39 disposed intermediate the under face of the wall 29 and a split washer 40 mounted in the groove 36, the normal tendency of the spring being to hold the die element in depressed position. When the die elements are mounted in the die carrier the extensions 32 extend inwardly and the tangs 33 extend downwardly into and through openings 41 arranged in spaced relationship in the annular flange 8 of the die carrier. The cross dimension of the tangs is such that the side

edges thereof bear against the walls of the openings 41, thus preventing rocking motion of the die elements in their supports whereby the die elements are guided to maintain them in proper cutting alignment with the punch elements.

It will be understood that by operation of the hand wheel 13 selected pairs of the punch and die elements are brought to the cutting point and the cutting operation performed by elevating the die element toward the punch element. The operating mechanism for effecting the upward movement of the respective die elements comprises a block 42 slidably mounted in a space between the walls 43 and 44 that are stationary parts of the end frame of the machine. The block 42 has a shank 45 that connects into a foot 46, said foot 46 extending inwardly subjacent to the lower end of the die element that is positioned at the cutting point. The foot 46 has a notch 47 in its upper face, said notch 47 conforming to the contour of the pointed extremity of the die element, so that when the foot is raised into contact with the end of the die element the shank thereof will be centered and preserved in vertical alignment for pressure against the corresponding punch element.

The mechanism for raising the foot 46 into contact with the shank of the die elements includes toggle links 48 and 49, the extremity of the link 48 being pivoted to a bracket 50 extending inwardly from the wall 43 of the end frame. The upper extremity of the link 49 is pivoted to a stud 51, said stud 51 being secured to the block 42 near its upper end. The toggle links 48 and 49 are pivoted together and to a link 52, said link 52 being pivoted to a rocker arm 53. The rocker arm 53 is mounted on a transverse shaft 54, said shaft 54 being journaled in the side walls of the end frame and having extensions beyond the side walls of the end frame at either side, thereby providing at each side of the machine a mounting for a removably attached operating handle 55. Provision is made for mounting the handle 55 either on the right or left end of the shaft so that the machine is adapted for convenient operation by either a right or left hand operator.

The rocker arm 53 has a hub 56 that has a segmental cut-out portion 57, and the shaft 54 carries a pin 58 that operates within the cut-out portion of the hub 56 to provide a lost motion to delay the action of the die operating mechanism in respect of the operation of the work feeding mechanism, as will be made clear from further description hereinafter.

In so far as the operation of the mechanism for elevating the die elements is concerned, it is sufficient at this point to say that after the handle is depressed through

the zone of the cut-out portion, the pin 58 makes contact with the wall of the hub 56, thereby causing a forward movement of the rocker arm 53 which, through the medium 5 of the link 52, spreads the toggle levers 48 and 49, the end of the lever 49 moving upwardly thereby moving the block 42 and the foot 46 carried thereby. Separate movement of the foot 46, after the end of the 10 shank of the die element has centered in the notch 47, elevates the die element into contact with the corresponding punch element, cutting the character in the work. After the cutting operation has been performed 15 the handle is released and returned to normal position by a spring 54^a attached to the shaft 54 and a relatively stationary part of the frame, and the die element, through the action of the spring 39 is depressed. In 20 order to insure the depression of the die element a release device in the form of an angular strip 59 is attached to the forward part of the foot 46, said strip extending upwardly and having a finger 60 extending 25 into the space between the top and lower walls of the cut-out portion 37 of the shank 35. Thus, if there is a tendency of the die element to stick in its elevated position, the finger 60 will contact with the bottom wall 30 of the cut-out portion 37 and pull the die element downwardly as the foot returns to normal or depressed position.

The paper feeding mechanism includes a carriage comprising a work supporting table 61 to the under face of which is attached a feed bar 62, said feed bar 62 having side channels therein in which are received the edges of walls 63 and 64 constituting a stationary part or upper wall of the end frame 40 of the machine, the feed bar 61 being slideable with respect to the walls 63 and 64. The work, in the form of a rectangular sheet 65 of stencil material, is placed on the work supporting table 61 and is held in position 45 by means of a clip device comprising a plate 66, with a downwardly deflected and expanded inner extremity 67, said plate being hinged to a bracket 68 rising from the upper outer face of the work supporting table 61. A spring device 69 tends to depress the outer 50 extremity 67 in pressure contact with the upper face of the stencil cutting material. A finger knob 70 is provided on the top wall of the plate 66 for elevating the clip device for the insertion of the work.

The mechanism for stepping the carriage transversely across the machine for feeding the work to the cutting point comprises an escapement mechanism including a rack 71, an escapement pawl 72 and actuating mechanism for the pawl. The pawl 72 is pivotally mounted on a stud 73, said stud being carried by the free end of a lever 74, the lever 74 being pivoted at 75 to a relatively stationary part of the machine. A spring

76 of the retractile type is connected at one end to a stud 77 carried by the frame of the machine and at the other end to a pin 78 on the side face of the lever 74. A second spring 79, also of the retractile type, is attached to said pin 78 at one end and at the other end to a pin 80 carried by the pawl 72. The hub of the pawl 72 carries a pin 81 which together with a pin 82 on the side face of the lever 74 constitutes a return stop device for the pawl. The stud 73 has sliding connection in a slot 83 in the end of a lever 84, said lever 84 being pivoted at 85 to a relatively stationary part of the machine. The operation of the mechanism for elevating the 75 lever 84 and thereby causing the operative contact of the pawl with the teeth of the rack 71 for stepping the carriage across the machine is accomplished by means of a cam 86 carried by the main operating shaft 54 of 80 the machine. The cam 86 contacts with a pin 87 carried by the lever 84.

As the operating handle is depressed the main operating shaft 54 is rocked, causing the cam 86 to contact with the pin 87 thereby 90 raising the lever 84 causing the upward arcuate movement of the pawl 72 into engagement with the rack teeth and the lateral stepping movement of the work supporting carriage.

The escapement mechanism is arranged so that the position of the work is accomplished before the stencil cutting operation becomes effective by reason of the fact that there is a retarded operation of the stencil cutting mechanism, due to the lost motion of the pin 58 in the cut-out segment 57 of the hub 56. That is to say, the first movement of the handle downwardly operates the escapement mechanism, positioning the work at the cutting point, and the further depression of the handle causes the cutting operation. When the handle is released both the work feeding mechanism and the stencil cutting mechanism are returned to normal position.

In order to provide for the manual lateral adjustment of the work supporting carriage handles 88 are provided at each side thereof.

A stripper device for stripping the work from the punch and die elements and also for guiding the work comprises the member shown in detail in Fig. 9. This member is formed from a flat strip of material bent upon itself to form leaves, the lower one of which has a projection 89 that is screwed to the under face of the wall 64. From the projection 89 the member extends forwardly forming the leaf 90 that has a cut-out portion 91 so that the die element may pass through said cut-out portion in its upward movement. The plate is then turned at 92, being deflected backwardly forming an upper leaf 93. The upper leaf 93 has a cut-out portion 94 through which the punch element extends and the extremity of the upper leaf 130

is deflected upwardly at 95 so as to form a guide way for the work. Obviously, after cutting operation if the work has a tendency to adhere to the die element as that element moves downwardly through the lower leaf of the stripper, the work will be released from the die restoring it to normal position at the cutting point.

It will be noted by reference to Fig. 1 that the upper wall of the frame of the machine is slightly extended at a point adjacent to the juncture of the end frame forming an angular upper wall at either side of the punch and die carriers. It will be noted also that there is provided on this upper wall a series of score lines 96, whereby the inward adjustment of the work may be determined.

From the foregoing it will be understood that the operation of the machine is briefly as follows: The work, in the form of stencil cutting material, such as a stiff cardboard or the like, is placed on the work carriage 61 the clip 66 being first raised by means of engagement with the knob 70 for the insertion of the sheet of stencil cutting material. The carriage 61 is then manually positioned at one side of the machine by engagement with the handle 88 and the work alined by means of the score lines 96. By operation of the hand wheel 13 the selected set of punch and die elements are positioned at the cutting point, the indices 22 and the pointer 23 being utilized for that purpose. Depression of the handle 55 first steps the carriage 61 one interval laterally, and a further depression causes the operation of the cutting mechanism in the manner described in detail in the foregoing specification. The release of the handle results in restoration of the mechanisms to initial positions.

It will be observed that all of the operating structure is subjacent to the work supporting carriage and that there is a clear field of vision by the operator to the cutting point so that the point on the work can be observed before the performance of the cutting operation. It will also be noted that provision for maintaining accurate alinement of the punch and die elements is made so that the machine will accomplish accurate work. It may also be noted that the adjustment of the machine for bringing the selected set of punch and die elements into cutting position is such that the machine may be operated very rapidly. It will also be observed that provision is made for stripping the work from the punch and die elements in such manner as to prevent any damage to the work sheet.

I am aware that modifications in the structure may occur to those skilled in the art, which modifications will be within the limitations of the invention. I do not restrict myself therefore to the exact structure shown and described.

What I claim and desire to secure by Letters Patent, is:—

1. In a stencil cutting machine, the combination with a main frame, of a rotary element including spaced carriers, an annular spaced series of punches carried on the under face of the upper one of said carriers, vertically movable die elements mounted in the lower one of said carriers, an actuator for moving the die element upwardly toward the punch elements when the same are brought to the cutting point, operating mechanism for moving said actuator upwardly, a work supporting carriage, escapement mechanism for said carriage, an operating shaft for operating said escapement mechanism and said actuator operating mechanism, and a handle for operating said shaft.

2. In a stencil cutting machine, the combination with a main frame, of a rotary element including spaced carriers, an annular spaced series of punches carried on the under face of the upper one of said carriers, vertically movable die elements mounted in the lower one of said carriers, a guide device in connection with said die elements for preventing rotary movement thereof, an actuator for moving the die elements upwardly toward the punch elements when the same are brought to the cutting point, operating mechanism for moving said actuator upwardly, a work supporting carriage, escapement mechanism for said carriage, an operating shaft for operating said escapement mechanism and said actuator operating mechanism, and a handle for operating said shaft.

3. In a stencil cutting machine, the combination with a main frame, of a rotary element including spaced carriers, an annular spaced series of punches carried on the under face of the upper one of said carriers, vertically movable die elements mounted in the lower one of said carriers, an actuator for moving the die elements upwardly toward the punch elements when the same are brought to the cutting point, a centering device between the actuator and the die elements for maintaining the punch elements in vertical alinement, operating mechanism for moving said actuator upwardly, a work supporting carriage, escapement mechanism for said carriage, an operating shaft for operating said escapement mechanism and said actuator operating mechanism, and a handle for operating said shaft.

4. In a stencil cutting machine, the combination with a main frame, of a rotary element including spaced carriers, an annular spaced series of punches carried on the under face of the upper one of said carriers, vertically movable die elements included in the lower one of said carriers, a guide device in connection with said die elements for preventing rotary movement thereof, an ac-

tuator for moving the die elements upwardly toward the punch elements when the same are brought to the cutting point, a centering device between the actuator and the die elements for maintaining the punch elements in vertical alinement, operating mechanism for moving said actuator upwardly, a work supporting carriage, escapement mechanism for said carriage, an operating shaft for operating said escapement mechanism and said actuator operating mechanism, and a handle for operating said shaft.

5. A stencil cutting machine, comprising a frame; a punch carrier; a die carrier; a rotatably mounted connection between said punch carrier and said die carrier whereby said carriers are supported in spaced relationship, the punch carrier above the die carrier, said connections being rotatably supported in respect of the frame; an operating wheel for rotating said connection; a pointer and dial construction for indicating the position of selected pairs of punch and dies carried by said carriers at the cutting point; a series of punch elements carried by said punch carrier; a series of vertically movable die elements carried by said die carrier; operating mechanism for operating the die elements positioned at the cutting point; a work supporting carriage; escapement mechanism for said carriage; and an operating rock shaft in connection with said die operating mechanism and said escapement mechanism whereby the escapement mechanism is stepped and the die operating mechanism actuated after the escapement mechanism has operated.

6. In a stencil cutting machine, a guide and stripper device comprising a metallic strip in the form of spaced upper and lower leaves arranged to receive the work between them and having openings therethrough for the operation of the cutting die elements; in combination with a rotary punch carrier operating above said guide and stripper device, punch elements supported by said carrier above the upper leaf of said guide and stripper device, upwardly movable die elements supported below said guide and stripper device, and mechanism for operating said die elements through the openings in said guide and stripper device to cooperate with said punch elements while the cutting point is visible to the operator.

7. In a stencil cutting machine, the combination of a stationary frame, a rotary carrier mounted on the frame, downwardly facing punch elements supported by the upper portion of the carrier, upwardly facing die elements supported by the lower portion of the carrier and corresponding in number to the number of punch elements, a stationary guide and stripper device supported by the frame extending between said die and punch elements and comprising

upper and lower leaves between the die and punch elements and arranged to receive the work between them and having openings therethrough for the operation of the die elements, and mechanism supported by the frame for operating any of said die elements after the carrier has been turned to place the punch and die elements in position for operation.

8. In a stencil cutting machine, the combination of a main frame, a lateral extension from one side of said frame, a rotary support within the main frame, a number of downwardly facing punch elements carried by the rotary support, a number of die elements mounted in said support for movement toward and away from said punch elements, a carriage supported by said lateral extension for tangential movement relative to said rotary support, means for supporting the stencil work on said carriage extended between said die and punch elements, mechanism supported by said lateral extension for raising said die elements to cut the work at points visible to the operator, and escapement mechanism operated as an incident to the operation of said last-named mechanism for stepping the carriage tangentially of the rotary support.

9. In a stencil cutting machine, the combination with a main frame having end frame extensions, of a stencil cutting mechanism rotatably mounted in the main frame, a carriage supported on the upper face of the end frame, escapement mechanism for said carriage whereby said carriage is stepped across the end frame for feeding the work to the cutting point, operating mechanism for the stencil cutting mechanism, an actuator for said escapement mechanism, a main shaft operatively connected with said actuator for said escapement mechanism and with the operating mechanism for said stencil cutting mechanism, and an operating handle removably attachable to said main shaft at either end thereof whereby the machine may be operated by a right or left hand operator.

10. In a stencil cutting machine, the combination with a frame, of stencil cutting mechanism mounted in said frame, a carriage for stepping the work across the cutting point of said stencil cutting mechanism, operating mechanism for said stencil cutting mechanism arranged below the upper face of the frame, actuating mechanism for said carriage, a rock shaft, and connections between said rock shaft for operating said stencil cutting mechanism and said escapement mechanism.

11. In a stencil cutting machine, the combination with a frame, of stencil cutting mechanism mounted in said frame, a carriage for stepping the work across the cutting point of said stencil cutting mecha-

nism, operating mechanism for said stencil cutting mechanism arranged below the upper face of the frame, actuating mechanism for said carriage, a rock shaft, connections between said rock shaft for operating said stencil cutting mechanism and said escapement mechanism, and a stripper device for the work.

12. In a stencil cutting machine, the combination with a frame, of stencil cutting mechanism mounted in said frame, a carriage for stepping the work across the cutting point of said stencil cutting mechanism, a clip device in connection with said carriage for holding the work in position on said carriage, operating mechanism for said stencil cutting mechanism arranged below the upper face of the frame, actuating mechanism for said carriage, a rock shaft, connections between said rock shaft for operating said stencil cutting mechanism and said escapement mechanism, and a stripper device for the work.

13. In a stencil cutting machine, the combination with a frame, of stencil cutting mechanism mounted in said frame, a carriage for stepping the work across the cutting point of said stencil cutting mechanism, a clip device in connection with said carriage for holding the work in position on said carriage, a dial on the upper face of the frame of the machine for alining the work in said carriage, operating mechanism for said stencil cutting mechanism arranged below the upper face of the frame, actuating mechanism for said carriage, a rock shaft, connections between said rock shaft for operating said stencil cutting mechanism and said escapement mechanism, and a stripper device for the work.

14. In a stencil cutting machine, a stationary frame; stencil cutting mechanism supported by said frame; a stripper device comprising a U-shaped plate extending between the cooperative parts of the stencil cutting mechanism and having holes therethrough for operation on the stencil cutting mechanism; a carriage; and means on the carriage for supporting the work between the arms of said U-shaped plate in position for operation of the stencil cutting mechanism.

15. In a stencil cutting machine, the combination with stencil cutting mechanism; of a carriage for feeding the work to the cutting point of said stencil cutting mechanism; and an escapement mechanism for said carriage comprising a rack on the carriage, a pawl, a lever pivoted to a relatively stationary part of the machine carrying said pawl, resilient means for holding said lever and said pawl in normal position for engagement with the rack, a second lever having pin-in-slot connection with said first-named lever and said pawl, said lever being

pivoted to a relatively stationary part of the machine, an operative shaft, a cam carried by said shaft, and connections between said last-named lever and said cam whereby upon the rocking of said shaft said escapement mechanism will be actuated to step the carriage across the machine.

16. In a stencil cutting machine, a punch carrier; a die carrier; die elements movably supported in said die carrier; punch elements rigidly supported in said punch carrier; an actuator for said die elements comprising a vertically slidable block mounted in the frame of the machine; a foot carried by said block; a pair of toggle levers pivoted together and having one of said levers pivoted to the block and the other of said levers pivoted to a relatively stationary part of the machine; a link pivoted to said toggle levers; a rocker arm; an operating shaft in connection with said rocker arm; and a handle for actuating said shaft.

17. In a stencil cutting machine, a punch carrier; a die carrier, die elements movably supported in said die carrier; means for guiding said die elements and preventing lateral motion thereof; punch elements rigidly supported in said punch carrier; an actuator for said die elements comprising vertically slidable block mounted in the frame of the machine; a foot carried by said block; a pair of toggle levers pivoted together and having one of said levers pivoted to the block and the other of said levers pivoted to a relatively stationary part of the machine; a link pivoted to said toggle levers; a rocker arm; an operating shaft in connection with said rocker arm; and a handle for actuating said shaft.

18. In a stencil cutting machine, a punch carrier; a die carrier; die elements movably supported in said die carrier; punch elements rigidly supported in said punch carrier; an actuator for said die elements comprising a vertically slidable block mounted in the frame of the machine; a foot carried by said block; centering means between the foot and the die elements for preserving the die elements in vertical alinement; a pair of toggle levers pivoted together and having one of said levers pivoted to the block and the other of said levers pivoted to a relatively stationary part of the machine; a link pivoted to said toggle levers; a rocker arm; an operating shaft in connection with said rocker arm; and a handle for actuating said shaft.

19. In a stencil cutting machine; a die carrier comprising a webbed annular member having spaced horizontal walls at its periphery, the upper one of said walls having an inclined upper face; a die element including a shank, said shank being mounted in the peripheral walls of the die carrier; a spring for holding the die element nor-

mally in depressed position; and an actuator for moving the die element upwardly in opposition to said spring.

20. In a stencil cutting machine, a rotary carrier having a pair of vertically spaced walls at its periphery, an annular series of U-shaped member above said walls, a die plate secured to the upper ends of the arms of each of said members, stems in connection with the lower ends of said U-shaped members extending downwardly through both of said walls, springs encircling said stems between said walls and having their upper ends bearing against the lower side of the upper wall, abutments on said stems engaged by the lower ends of said springs, an element supported below said carrier, lever mechanism for raising said element to engage the lower ends of said stems respectively to raise said stems and said dies in opposition to said springs, and a device in connection with said element for engaging said stems respectively to lower them after they have been raised.
25. 21. In a stencil cutting machine, a rotary carrier having a pair of vertically spaced

walls at its periphery, an annular series of U-shaped members above said walls, a die plate secured to the upper ends of the arms of each of said members, stems in connection with the lower ends of said U-shaped members extending downwardly through both of said walls, springs encircling said stems between said walls and having their upper ends bearing against the lower side of the upper wall, abutments on said stems engaged by the lower ends of said springs, an element supported below said carrier, lever mechanism for raising said element to engage the lower ends of said stems respectively to raise said stems and said dies in opposition to said springs, a device in connection with said element for engaging said stems respectively to lower them after they have been raised, and annular series of 30 punch elements corresponding to said die elements supported by said carrier, and a stationary guide and stripper device for the work extending between said die and punch elements.

STEPHEN D. HARTOG.
